US00D600243S

(12) **United States Design Patent**
Miyaji et al.

(10) **Patent No.:** US D600,243 S
(45) **Date of Patent:** ** Sep. 15, 2009

(54) **MOBILE INFORMATION TERMINAL**

(75) Inventors: **Taihei Miyaji**, Tokyo (JP); **Kaori Ito**, Kanagawa-ken (JP)

(73) Assignee: **Kabushiki Kaisha Toshiba**, Tokyo (JP)

(**) Term: **14 Years**

(21) Appl. No.: **29/321,345**

(22) Filed: **Jul. 15, 2008**

(30) **Foreign Application Priority Data**

Feb. 8, 2008 (JP) 2008-002758

(51) **LOC (9) Cl.** 14-02

(52) **U.S. Cl.** D14/346

(57) **CLAIM**

The ornamental design for a mobile information terminal, as shown and described.

DESCRIPTION

FIG. 1 is a bottom, front and left side perspective view a mobile information terminal showing our new design,

FIG. 2 is a bottom, front and left side perspective view with a numeric keypad being in use thereof,

FIG. 3 is a bottom, front and left side perspective view with a keyboard being in use thereof,

FIG. 4 is a front elevational view thereof,

FIG. 5 is a rear elevational view thereof,

FIG. 6 is a left side elevational view thereof,

FIG. 7 is a right side elevational view thereof,

FIG. 8 is a top plan view thereof,

FIG. 9 is a bottom plan view thereof,

FIG. 10 is a front elevational view with the numeric keypad being in use thereof,

FIG. 11 is a bottom plan view with the numeric keypad being in use thereof,

FIG. 12 is a front elevational view with the keyboard being in use thereof; and,

FIG. 13 is a right side elevational view with the keyboard being in use thereof.
